UNITED STATES PATENT OFFICE.

GEORGE T. MCLEOD, OF BOSTON, MASSACHUSETTS, ASSIGNOR TO THOMAS G. PLANT COMPANY, OF ROXBURY, BOSTON, MASSACHUSETTS, A CORPORATION OF MASSACHUSETTS.

SHOE.

Application filed August 18, 1920. Serial No. 404,314.

To all whom it may concern:

Be it known that I, GEORGE T. MCLEOD, a citizen of the United States, and a resident of Boston, county of Suffolk, and State of 5 Massachusetts, have invented an Improvement in Shoes, of which the following description, in connection with the accompanying drawings, is a specification, like characters on the drawings representing like 10 parts.

This invention relates to boots and shoes and the particular purpose is to provide an article of footwear which may be manufactured in an easy and expeditious manner and 15 which will be of great lateral flexibility.

The invention may be considered an improvement in the production of shoes having a "released" or "unlocked" shank portion of the type originally described in United 20 States Patent to William J. MacFarland, No. 1,101,747. My invention simplifies the process of making a shoe and particularly a welt shoe of this kind and permits it to be produced without modifying the present established methods and routine of a modern 25 shoe factory.

My invention may best be understood by reference to the following description of one 30 illustrative embodiment thereof which I have shown by way of example in the accompanying drawings, wherein:

Fig. 1 is a bottom plan of a shoe;

Fig. 2 is a similar view with the outsole removed;

35 Figs. 3 and 4 are sections of the shoe on the last taken on the lines 3-3 and 4-4 of Fig. 2, respectively; and

Fig. 5 is a side elevation of an insole utilized in the form of invention illustrated.

40 In the form of my invention here shown by way of illustration I utilize as adaptable for the purposes thereof by suitable preparation an insole of known construction comprising an inner leather thickness 7 pro- 45 vided with a marginal lip 9 and reinforced preferably by a thickness of canvas 11 overlying the shank and forepart of the sole and marginally secured to the lip 9. For the

50 purpose of my invention the lip 9 is, however, severed from the main body portion of the insole proper 7 along the inner side of the shank as shown in Figs. 3 and 5 between the points *a* and *b* (Fig. 2), this operation providing an insole which is cut in-

wardly along the side of the shank and 55 across the major portion of the width thereof, thus providing a lip which is released from the body of the insole. The outer thickness of the insole, provided by one or more canvas layers 11, is secured adjacent 60 the heel seat at the left of the point *a* in Fig. 2, detached along the inner side of the shank between *a* and *b* and marginally attached to the leather 7 from the point *b* around the toe and to the heel seat on the opposite side. 65 The intermediate portion of the canvas layer 11 is free so that at the shank of the shoe this outer thickness of the insole is secured only along the outer side.

The insole comprising the layers 7 and 11 70 may be attached to the last in the usual way and the upper 13 applied to the last and a welt 17 may be utilized extending completely around the shoe on both sides to the heel seat. The upper 13 and welt 17 as 75 shown in Figs. 3 and 4 are sewed in the usual manner to the lip 9 of the insole. Referring to Fig. 3 it will be seen, however, that the inner thickness of the insole which is presented to the wearer's foot is free at the inner side of the shank from the upper and welt, the upper and welt there being secured to the outer thickness 11. It will be understood that the outsole 19 shown in Fig. 1 is attached to the welt 17 in the usual manner. 80 85

The detached portion of the insole along the shank portion of the shoe provides a portion which can buckle if the shoe is distorted laterally. This provides a shoe of great flexibility in this direction and one 90 which adapts itself freely to the variations in the form of the wearer's foot. This lateral flexibility also greatly facilitates putting the shoe on and taking it off. The buckled portion shown in Fig. 5 further 95 rests in the arch of the foot and acts as a more or less resilient arch support without, however, binding or exerting any undue pressure.

I should point out that the only extra operation involved in constructing this shoe over the usual process of constructing shoes of like type is the slitting between the points *a* and *b*. There are no extra parts to be manipulated and the continuity of the usual 100 inseam and of the welt, if one is employed, is preserved. This slitting operation can be 105 easily and quickly performed at any time

before the outsole is applied either before or after the inseaming operation and either before or after the insole is applied to the last.

I have herein illustrated and particularly 5 described the manufacture of a welt shoe utilizing a so-called "Gem" insole, that is, one with a reinforcing layer of canvas, yet obviously my invention is not limited to the use of such an insole, and the sewing 10 rib of the insole where it is desired to have the shoe "unlocked" may be severed from the body of the insole whether the insole is reinforced or not.

Having described in detail the particular 15 form of my invention shown by way of illustration in the accompanying drawings, the principles exemplified thereby which I claim as new and desire to secure by Letters Patent I shall express in the following 20 claims.

1. In a shoe an insole comprising an inner layer having a peripheral lip extending continuously around the foreport and shank thereof, an outer layer having a portion 25 underlying the shank of said inner layer and secured marginally to said lip, an intermediate portion of the lip being severed from the body of the said inner layer at the inner side of the shank, an upper and an 30 outsole, said upper and outsole being secured to said lip.

2. In a shoe a leather insole proper having a marginal lip, a reinforcing canvas layer marginally secured to said lip, said 35 lip being severed from the insole proper along the inner side of the shank, an upper and a welt extending continuously from one side of the heel around the forepart of the shoe to the other side of the heel, said 40 upper and welt being seamed to said lip.

3. In a shoe an insole having an inner layer and an outer layer, said outer layer being secured marginally to said inner lay-

er from a point adjacent the heel seat on one side around the toe to a point in advance 45 of the shank at the other side, and being free of the inner layer from said point to adjacent the heel seat, and an upper and an outsole, said upper and outsole being marginally secured to said outer layer. 50

4. An insole for shoes comprising a leather insole proper having a marginal lip and an outer reinforcing layer secured at both sides to said lip, said lip being severed from the insole proper along the inner side of the 55 shank.

5. The process of making welt shoes which comprises providing an insole with a marginal lip, securing a reinforcing layer thereunder to the said lip, severing the lip from the body of the insole at the shank and inseaming the upper to said lip. 60

6. In a shoe an insole having the body thereof cut to provide a marginal lip for attachment of the shoe upper, a portion of 65 said lip along the shank being severed from the body of the insole.

7. The process of making shoes wherein an insole is provided with a sewing rib, an upper and welt is attached to the rib and an outsole to the welt characterized by the 70 step of severing a portion of the rib from the body of the insole at any time during the process of manufacture prior to the attachment of the outsole. 75

8. The process of making shoes wherein an insole is provided with a sewing rib, an upper and welt is attached to the rib and an outsole to the welt characterized by the 80 step of severing the rib from the body of the insole along the inner side of the shank at any time during the process of manufacture prior to the attachment of the outsole.

In testimony whereof, I have signed my name to this specification.

GEORGE T. McLEOD.
